Colgate-Palmolive-Peet Company, Jersey City,
N. J., a corporation of Delaware

Application March 23, 1944, Serial No. 527,694

10 Claims. (Cl. 242—75)

This invention relates to wrapping machines and more particularly to a machine for controlling the tension applied to a web of wrapping material during unwinding from a storage reel.

Most wrapping machines, regardless of structural detail, include a wrapping material storage reel, means for unwinding the wrapping material from that reel, means for cutting the wrapping material into sheets of adequate size to accommodate the particular article to be wrapped and means for folding and sealing the cut sheets about the article.

In general, a wrapping material for use in connection with small articles such as bars of soap is prepared in the form of a continuous band of substantial width. This band is printed with whatever indicia the wrapped articles are to bear and at the same time is perforated marginally of the printed areas. Thereafter the wide band is wound about a hollow cop or tube and the resulting cylindrical body is radially slit into a plurality of narrow wound bodies, the webs of which are each stored on a cop or tube for unwinding during use.

For the wrapping operation, the cop is mounted over a rotatable support and the roll of wrapping material is unwound therefrom by frictional draw-off rollers which grip successive portions of the web between their circumferential faces. After leaving the draw-off rollers, the perforated margins of the web are engaged by a sprocket device and cutter, the registry of the sprockets with the perforations serving to insure the cutting of the web at properly timed intervals consistent with the printed indicia which each wrapped article is ultimately to bear.

The success of the foregoing arrangement has very largely depended upon the positiveness of the drive of the draw-off rollers which operate by friction. If the draw-off were to be effected by the sprocket devices themselves, there would be too much tendency to tear the web perforations due to the web tension between the roll of material and the sprockets. To avoid this tension, frictional draw-off rollers are provided, these rollers serving, in theory, to feed the web to the sprocket devices under substantially no tension so as to prevent tearing of the marginal perforations of the web by the sprockets. The arrangement just described, although theoretically satisfactory, is not in practice wholly desirable for serious difficulty has been encountered in preventing slippage between the draw-off rollers and the wound roll of wrapping material, such slippage resulting in increases in tension between the

draw-off rollers and the sprocket devices of such a magnitude as to cause rupture of the margins of the web resulting in the operation of the cutting mechanism out of synchronism with the printed indicia on the web. As a consequence of this, the articles may be incompletely wrapped or the printed material may be wrongly located on said articles.

Upon analysis of the foregoing problem it was found that, because the reel is initially of great diameter and the force exerted by the draw-off rollers is a constant, there is a high starting torque tending to rotate the reel. During the unwinding operation this torque is progressively reduced as a function of the reduction in diameter of the web on the reel. Thus the draw-off rollers tend to rotate the reel too rapidly during the initial stage of unwinding, causing excessive slack between the reel and said rollers while, during the latter stages of unwinding, the torque is so low that the rollers may slip relative to the web in attempting to rotate the reel.

Once the foregoing problem was recognized, efforts were made to control tension. Among these were suggestions that a brake be applied to the reel in opposition to the high starting torque. During unwinding the operator could gradually release this brake so that there would be virtually no opposition to the low torque value existing near the end of the unwinding operation. This arrangement is satisfactory subject to constant attention by the operator. Such constant attention is, however, difficult to maintain and, even if maintained, not economically feasible. Other braking arrangements in which the braking effect could be automatically reduced during unwinding were unsatisfactory either because of the complexity of the machinery involved or because of reliance on unsound principles of engineering.

With the foregoing in mind it is an object of this invention to overcome the difficulties encountered in the prior art in connection with the maintenance of tension between a storage reel and the draw-off rollers associated therewith by providing resilient braking means normally acting on the reel to retard rotation thereof and means for progressively reducing the loading of said resilient means at a rate and of a magnitude correlated with the rate and magnitude of diameter reduction whereby the arrangement is susceptible to use without adjustment with webs of varying thickness unwound at various speeds.

It is contemplated according to this invention that the foregoing objects be accomplished con-

comitantly with continuous operation in which an exhausted reel is replaced by a full one during the unwinding of another full reel, both reels being subject to tension control during their respective periods of unwinding.

Other objects and advantages of this invention will be apparent from a consideration of the following detailed description of a preferred embodiment thereof in conjunction with the annexed drawings, wherein:

Figure 1 is a vertical sectional view of a pair of package supports, the brake engaging and releasing elements being shown in front elevation;

Figure 2 is a view in section taken along the line 2—2 of Figure 1;

Figure 3 is a view in section taken along the line 3—3 of Figure 1; and

Figure 4 is a perspective view of the apparatus of Figure 1 showing a reel of wrapping material in operative position and indicating in broken lines the movement of portions of the brake releasing elements during an unwinding operation.

The apparatus illustrated in the foregoing figures of the drawings constitute but a part of a wrapping machine of a type in which a printed wrapper in the form of a continuous band is withdrawn from a reel and cut at regular intervals for wrapping about a bar of soap or other article. The continuous strip or band 8 is withdrawn from the storage reel by two draw-off rolls, not shown, operating in peripheral contact on either side of the band or strip. A pull of constant force, such as is exerted by the unwinding rolls on the band, produces a torque equal to the product of that force times the effective radius of the reel from which the band is being unwound. When the reel is full this radius is large resulting in a high torque but as the band is unwound the effective radius decreases with a resulting decrease in torque which may cause slippage between the draw-off rollers and the band. Since such slipping may result in disruption of the synchronism between the cutter and the printed material 9 on the continuous band, it is proposed according to this invention to apply a resilient braking force on the reel during the initial stages of unwinding and to progressively decrease this force responsive to reductions in the effective diameter of the reel which results in reduced torque during the end winding period.

In order to understand how the braking force is applied and reduced it will be necessary first to consider the supports for holding the wrapper containing reels.

The rolls of wrapping material each wound on a cop or tube are supported on spindle assemblies 10 and 11 which in turn are supported from a plate 12 which acts as a supporting element not only for said assemblies but as well for the braking apparatus to be hereinafter more fully described. Inasmuch as assemblies 10 and 11 are identical in structure and function, only one of them will be described in detail.

In connection with assembly 11 it should be noted that a stud 13, threaded at its ends, is anchored in bearing 14 by a nut 15 to plate 12, the free end of the stud extending outwardly from the plate a distance somewhat in excess of the axial width of the roll to be supported thereon. Mounted for free rotation on stud 13 is a sleeve 16 having a flange 17 at the end thereof remote from plate 12. Overlying sleeve 16 and splined for rotation therewith is a brake sleeve

element 18 having a circumferential groove 19 in its exterior surface functioning as a drum receiving thereon brake shoes 20 and 21 which are pivoted respectively to stationary bolts 22 and 23 passing through plate 12 and anchored thereto by nuts such as 24, see Figure 2. It can now be seen that when brake shoes 20 and 21 are compressed against the grooved drum area 19 of brake sleeve 18, the rotation of the latter about stud 13 will be retarded. So that this retardation may be effective on the roll of wrapping material, the latter is indirectly connected to sleeve 16. To this end flange 17 of sleeve 16 is bolted to a flange 25 of reel support 26. Reel support 26 comprises, in addition to flange 25, an integral semi-cylindrical portion 27 extending for about 180° around stud 13 and terminating in an annular portion 28 having an interior central bore of a diameter greater than the external diameter of stud 13. Interposed between annular end portion 28 and stud 13 is a sleeve 29 having thereon a shoulder 30. The portion of this sleeve which is of lesser external diameter is of a size to receive thereover, in bearing engagement, annular portion 28 of reel holder 26. Between annular portion 28 and shoulder 30 there is interposed an annular lubricating washer 31. A similar washer 32 is disposed at the other end of annular portion 28. Surrounding sleeve 29, at a point between washer 32 and the end of said sleeve, is an annular bearing element 33. This element is attached to sleeve 29. Sleeve 29 is keyed to stud 13 by a slot and pin arrangement, a pin 34 projecting radially from stud 13 and engaging in an axially extending slot 35 through sleeve 29 at its left hand end as viewed in Figure 2. Because slot 35 is of greater length than the diameter of pin 34, sleeve 29 is susceptible to axial movement on stud 13. This movement is controlled by an adjusting nut 36 threadedly engaging the end of the stud and connected to the sleeve 29 by an adjusting nut retainer 37 which locks the nut to the sleeve so that the latter moves positively with the former.

A leaf spring 38 extends from the top of annular portion 28 of reel holder 26 rearwardly through a slot 39 in flange 25 and through a registering slot 40 in flange 17. A counterweight 41 is integral with flange 25, lying 180° away from the mass of reel holder 26. A paper roll stop disc 42 is fastened to flange 25.

Upon reference to Figure 4, it can be seen that a reel of paper supported on a hollow cop or tube C is held in unwinding position by engagement between the interior walls of the tube and the exterior surface of reel holder 26, spring 38 exerting sufficient force to lock cop C and reel holder 26 for rotation as a unit. As the roll is placed in position the cylindrical interior of cop C compresses spring 38 from its reposed position and is then axially moved until one vertical wall of the roll abuts against paper stop disc 42. If then, the marginal perforations of the web do not correctly register with the sprockets of the cutter, adjusting nut 36 is turned to change the axial position of the marginal perforations. This adjustment is of small magnitude seldom amounting to an eighth of an inch. However, because brake sleeve 18 and flanged sleeve 16 are splined together, relative axial movement of these two elements is possible without disrupting the position of the brake sleeve 18 which is held by brake shoes 20 and 21 lying within the groove at 19.

Reel holder 11 which has just been described

is similar in all respects to reel holder 10 and corresponding parts have been designated by like numerals followed by the suffix "a." It is intended that while one of the reels on either holder 10 or 11 is being unwound the other reel may be changed for the purpose of replacing an empty one by a full one. The braking arrangement operates on either reel regardless of which is being unwound at any particular time. Since the braking force exerted by brake shoes 20 and 21 is to be reduced proportionately to the reduction in diameter of that reel as it is unwound, a follower wheel 50 is provided to contact the periphery of the wound band of wrapping material on the reel. Since follower 50 contacts the top tangent point of the reel it will maintain contact therewith by gravity throughout the unwinding operation.

Follower wheel 50 is pivoted between the shanks of a yoke 51 constituting one end of a lever 52. The other end of lever 52 is keyed at 53 to a sleeve 54 which is rotatably supported on a stud 55. This stud is threaded at one end for passage through plate 12. The stud is therefore held in position extending outwardly from the plate by a nut 56. The sleeve 54 is held against axial displacement on stud 55 by an annular washer 57 held in position by a bolt 58. The end of sleeve 54 remote from washer 57 is provided with a flange 59 which is attached to cam 60. Cam 60 is a thick disc-like plate having a rear wall adjacent and parallel to plate 12. The front face is recessed to define cam surfaces 61 and 62 and an intermediate neutral zone therebetween, while a hub 63 functions as a central reinforcement. In front of, but spaced from hub 63, is a sleeve 64 which is also keyed to sleeve 54. Between hub 63 and sleeve 64 the shanks of a yoke 65 are passed, the distance between said shanks corresponding to the external diameter of sleeve 54. Just below the point of origin of the shanks of yoke 65, a pin 66 is passed therethrough having on one end thereof a roller 67 mounted for free rotation. Said roller is in a position to follow the contour of cam surface 62 as indicated in Figure 3. A rod 68 is connected to the lower end of yoke 65, said rod being guided for vertical movement in a bearing 69 connected by bolts 70 to plate 12. The lower end of rod 68 is attached to a cross-head 71 through the opposite ends of which spring guides 72 and 73 are passed. These spring guides are threaded at both ends and at the upper ends are provided with nuts 74 and 75. At the lower ends they are provided with knurled adjusting nuts 76 and 77 while, between said adjusting nuts and the cross-head 71, coil springs 78 and 79 are disposed surrounding the spring guides.

Brake operating levers 80 and 81 are pivoted respectively to plate 12 at 82 and 83. One end of the lever 81 is provided with a hole so that it may fit over spring guide 73 with the defining edges of the hole resting on the top of coil spring 79. There is a similar arrangement in the case of lever arm 80, spring guide 72 and spring 78. It can now be seen that the end of lever 81 remote from spring guide 73 and on the opposite side of pivot point 83 is urged in a counterclockwise direction as viewed in Figure 1. The same situation obtains in connection with lever 80 except the corresponding portion thereof is urged in a clockwise direction as viewed in Figure 1. At the ends of levers 80 and 81 remote respectively from spring guides 72 and 73 connecting links 84 and 85 are pivotally attached respectively at 70 75

and 87. The ends of these links are attached at 88 and 89 respectively to toggles 90 and 91 respectively. The toggle arms of toggle 91 are pivotally connected at 92 and 93 to the ends of brake shoes 20 and 21, said shoes being normally urged apart by internal spring 94. Corresponding parts function in a corresponding manner in connection with reel supporting assembly 10. It can now be seen that spring 79 acting on lever 81 tends to shorten the distance between pivot points 92 and 93 thus drawing together brake shoes 20 and 21 against the action of spring 94. This causes the brake shoes to press against the brake drum at 19, so tending to retard rotation of the reel support to which the reel is locked by action of leaf spring 36. However, as follower wheel 50 moves inwardly toward the axis of reel supporting assembly 10, due to the unwinding of material from the reel, cam 60 will be turned in a clockwise direction as viewed in Figure 1 causing cam face 62 to gradually lower cam follower 67 which in turn will lower rod 68 and cross-head 71 thus disposing the upper edges of adjusting nuts 76 and 77 in a lower horizontal plane. This increases the distance between said nuts and levers 80 and 81 so that the springs 78 and 79 are less compressed and therefore exert less thrust against the respective levers permitting springs 94 and 94a to spread pivot points 92 and 93 of toggle 91 and 92a and 93a of toggle 90 to a slight extent thereby somewhat releasing the brakes.

It is to be understood that cam surfaces 61 and 62 are of substantially straight line development, i. e., the movement of follower 67 varies substantially in direct proportion to angular displacement of the cam throughout its active arc of movement. Since this is true it is evident that the release of the brakes will vary substantially in direct proportion to the reduction in diameter 40 of the web of wrapping material on the reel. The rate of brake release will be varied automatically with the rate of unwinding, regardless of the speed of operation of the draw-off rollers or the thickness of material 8.

In Figure 1 there is a diagrammatic indication of a partially exhausted roll on reel supporting assembly 10. While this roll is being unwound a full reel may be placed on the equivalent assembly 11. Then when the reel on assembly 10 is exhausted it is only necessary for the operator to swing lever 52 180° in a counterclockwise direction as viewed in Figure 1 so as to place follower wheel 50 in contact with the band of material on the reel supported by assembly 11. This action turns cam 60 180° and brings cam face 62 into co-action with follower 67 rather than cam face 61. Once this is done the operation is repeated as before, see Figure 4. The follower wheel 50 will cause lever 52 to turn in a counterclockwise direction as the reel is exhausted and thus follower 67 will gradually lower cross-head 71 to release the compression of springs 78 and 79.

While it is true that springs 78 and 79 are unloaded simultaneously according to the requirements of but one reel the braking effect on the other reel is immaterial due to the fact that it is not supplying material to the draw-off rollers at that time.

What is claimed is:

1. In a web tension control apparatus including a pair of supports mounted for rotation about spaced fixed axes, each adapted to receive thereover a roll of web material for rotation therewith, braking means normally acting on each support to retard rotation thereof, means connected to

both braking means for simultaneously reducing the braking effect thereof, and roll diameter sensing means for operating the means for reducing the braking effect, said sensing means being shiftable to sensing relationship with a roll of web material on either of said supports, whereby the apparatus may be continuously operated by placing a full roll on one of the supports while a roll on the other is being unwound and after completion of that unwinding, shifting the sensing means to operate with the full roll. 10

2. In a web tension control apparatus including a pair of rotatable supports mounted for rotation about spaced fixed axes, each adapted to receive thereover a roll of web material for rotation therewith, a brake drum fixed to each support, brake shoes acting on each drum, separate spring means each for urging the brake shoes acting on one of the drums to braking position, means for independently preloading each spring means, and means responsive to reduction in the diameter of a roll on one of said supports for simultaneously equally reducing the loading on both of said spring means at a rate and magnitude correlated with the rate and magnitude of the roll diameter reduction, said roll diameter reduction responsive means being movable to act with a roll on either support, whereby the machine may be continuously operated by placing a full roll on one of the supports while a roll on the other is being unwound and after completion of that unwinding, shifting the roll diameter reduction responsive means to operate with the full roll. 20

3. In a web tension control apparatus including a pair of rotatable supports each adapted to receive thereover for rotation therewith a roll of web material; a brake drum fixed to each support, brake shoes acting on each drum, independent spring means for urging the brake shoes acting on each drum to braking position, cam means having two cam surfaces developing in the same way from a reference point, means pivotally mounting said cam means intermediate said supports, a lever connected to said mounting means, a follower on said lever in position to contact a roll of web material on either of said supports by rocking of the lever from one to the other, and a cam follower for simultaneously reducing the thrust of both the said independent spring means in response to angular displacement of said cam means. 30

4. In a web tension control apparatus, a pair of rotatable roll holders each adapted to mount a roll of web material, a brake for each roll holder, a movable cam, a shiftable roll diameter sensing member for actuating said cam adapted to be selectively associated with a roll on either of said

roll holders, and a follower for said cam operatively connected to said brakes. 5

5. In a web tension control apparatus, a pair of rotatable roll holders each adapted to mount a roll of web material, a brake for each roll holder, a cam rotatable about an axis, a lever rigid with said cam and movable about said axis in response to changing diameter of an associated roll, said lever being shiftable for operative association with a roll on either of said roll holders, and a follower for said cam connected operatively to said brakes. 15

6. In a web tension control apparatus, a pair of spaced rotatable roll holders mounted for rotation about spaced fixed axes and each adapted for mounting a roll of web material, a brake for each roll holder, and brake control means comprising a movable member adapted to change its position in response to changes in diameter of an operatively associated roll, said member being shiftable mounted to be selectively placed in operative association with a roll on either of said roll holders. 20

7. In a web tension control apparatus, a pair of spaced rotatable roll holders mounted for rotation about spaced fixed axes and each adapted for mounting a roll of web material, a brake for each roll holder, a pivoted sensing member adapted to be selectively swung into operative association with a roll on either of said roll holders and responsive to changes in diameter of said associated roll, and brake control means actuated by said sensing member. 25

8. In a web tension control apparatus wherein a single roll diameter sensing member is adapted to be selectively associated with a roll of web material on either of two rotatable roll holders, said sensing member comprising a pivoted lever, a rotatable cam actuated by said lever, a single cam follower operatively connected to brakes for both of said roll holders, and spaced control surfaces on said cam one of which is adapted to co-act with said follower when said lever is moved into association with one or the other of said roll holders. 35

9. In the web tension control apparatus defined in claim 8, said cam and lever being rigid and rotatable about a common axis. 40

10. In a web tension control apparatus, a pair of rotatable roll holders mounted for rotation about fixed spaced axes each adapted to mount a roll of web material, a brake for each roll holder, and shiftable roll diameter sensing means adapted to be selectively associated with a roll on either of said roll holders operatively connected to said brakes. 50

HARRY F. CHILDERS.
